CLAIM

The ornamental design for a garden utensil, as shown or
described.

DESCRIPTION

FIG. 1 is a perspective side view of a garden utensil
showing our new design;

FIG. 2 is a similar perspective view thereof with the
utensil's hand grip shown detached from the handle;

FIG. 3 is a side elevational view thereof;

FIG. 4 is a top plan view thereof;

FIG. 5 is a front end elevational view thereof;

FIG. 6 is a rear end elevational view thereof; and

FIG. 7 is a bottom plan view thereof.

FIG. 5

FIG. 6

FIG. 7
